UNITED STATES PATENT OFFICE.

DAVID PETRI-PALMEDO, OF HOBOKEN, NEW JERSEY, ASSIGNOR TO THE MERGENTHALER LINOTYPE COMPANY, A CORPORATION OF NEW YORK.

LINOTYPE-MACHINE.

No. 796,859.

Specification of Letters Patent.

Patented Aug. 8, 1905.

Application filed February 2, 1905. Serial No. 243,839.

To all whom it may concern:

Be it known that I, DAVID PETRI-PALMEDO, of Hoboken, county of Hudson, and State of New Jersey, have invented a new and useful Improvement in Linotype-Machines, of which the following is a specification.

My invention has reference to Mergenthaler linotype-machines of the general character shown in United States Letters Patent No. 436,532. As these machines are ordinarily constructed the inclined channeled magazine receives the matrices at its upper end from the overlying distributor through a curved channeled throat or guide plate. The matrices falling from the distributor into the channels of this throat-plate descend therethrough by gravity and pass into the corresponding channels of the magazine. It occasionally happens that the channels get out of line and that the matrices will lodge in them at or near the upper end of the magazine, so that it becomes necessary to gain access to the channels. Heretofore it has been customary to cut back or shorten the top plate of the magazine and to close the opening thus made by a plate or bar hinged to the magazine, so that it may be turned upward at will. The employment of this plate is objectionable, because it reduces the length of the available channels and the number of matrices which may be stored in the magazine and also because it is a matter of annoyance and liable to be broken or bent when the magazine is removed from the machine, this removal being frequently made in order to permit the substitution of another magazine containing matrices of a different font.

The aim of my invention is to provide cheaper and more convenient means which will serve the double purpose of giving access to the channels and of closing the upper end of the magazine when it is detached from the machine in order to prevent the accidental escape of matrices or the entrance of foreign matter.

To this end it consists, broadly, in combining with the upper end of the magazine a hinged plate which will overlie the throat or entrance and serve as a cover therefor when the machine is in action and also serve when the magazine is removed as a cover or lid for its end.

Referring to the drawings, Figure 1 is a lon-

itudinal vertical section through the receiving end of the magazine and the throat or entrance with my improvement applied, the parts being in operative position. Fig. 2 is a sectional view of the upper end of the magazine removed from the machine with the lid or cover closed. Fig. 3 is a rear view of one side of the hinged plate shown in Fig. 1. Fig. 4 is a perspective view of the upper part of the magazine with the lid or cover down over the mouth.

Referring to the drawings, A represents the channeled magazine, composed of parallel top and bottom plates having their inner surfaces provided with longitudinal grooves or channels to receive and guide the upper and lower edges of the matrices B.

C represents a channeled guide or entrance which receives the matrices from the distributor and delivers them into the magazine. This entrance in modern machines is ordinarily hinged to the main frame, as shown at D, or otherwise mounted so that it may be turned backward away from the magazine and so that it may remain upon the main frame when the magazine is removed.

I construct my magazine with both the top and bottom plates extended to its upper end, as shown, and to the top of the magazine I connect a transverse plate E by hinged joints F of any suitable construction. In the form shown the jointed or hinged connection consists of an annular plate or ring f, secured to the end of the plate E and arranged to revolve around the circular hub or projection f', secured to the side of the magazine. The center of this joint is coincident with the upper corner of the magazine in order to permit the described motion of the plate. The only requirement is that the center of the hinge or joint should be located to admit of the plate E closing over and against the end of the magazine, as shown in Fig. 2, or swinging upward to the position shown in Fig. 1 to admit the matrices thereunder to the magazine. When the parts are in operative position, this plate rests upon and serves as a portion of the top of the throat C, closing its channels at the top and preventing the accidental upward escape of the matrices, which are compelled to pass thereunder into the magazine. While the machine is in action this plate may be turned upward and backward, as indicated in dotted lines in Fig. 1,

to give access to the channels of the throat and of the upper end of the magazine. When the magazine is removed from the machine, the plate may be turned downward across its end, as shown in Fig. 2, in which position it serves as a cover or lid, effectually closing the end of the magazine.

It will be observed that the jointed plate assumes in practice three positions—one for the purpose of closing the end of the magazine, another for the purpose of overlying and guiding the matrices as they pass into the magazine, and a third for the purpose of giving access to the upper edges of the channels in the throat through which the matrices pass to the magazine.

The hinge connections may be of any suitable construction which will permit the movement referred to.

Locking devices of any suitable character may be employed to hold the plate E in its closed position.

The lock or device shown in the drawings consists of a spring-arm f^2 , secured to the turning member f and provided with locking-pins f^3 , extended inward and adapted to engage in a corresponding cavity in the member f' , as plainly shown in Fig. 2.

Having described my invention, what I claim is—

1. The detachable channeled linotype-magazine substantially as shown, in combination with the transverse plate E, jointed to its upper end and adapted to assume three

positions, for the purposes, respectively, of closing the end of the magazine, or overlying and guiding the ingoing matrices, and of giving access to the channels through which the matrices enter.

2. In a linotype-machine, the combination of a removable magazine, A, a throat or entrance, C, communicating therewith, and a cover-plate, E, hinged to the magazine, for the double purpose of affording access to the channels when the parts are in operative position, and of closing the magazine when the latter is removed.

3. In a linotype-machine, the combination of the magazine A, the channeled throat C, communicating therewith, and a cover-plate E, jointed to the upper side of the magazine and adapted to overlie the throat when the magazine is in action, and to close the end of the magazine when it is removed.

4. In a linotype-machine, the combination of the magazine A, the coöperating throat C, mounted to turn backward from the magazine, and a cover-plate E, hinged to the magazine and adapted to close its end when the throat is removed, substantially as described and shown.

In testimony whereof I hereunto set my hand, this 27th day of January, 1905, in the presence of two attesting witnesses.

DAVID PETRI-PALMEDO.
